By Walter D. Murray

Attorney

UNITED STATES PATENT OFFICE.

NATHANIEL YATES, JR., OF AUGUSTA, KENTUCKY, ASSIGNOR TO THE F. A. NEIDER COMPANY, OF AUGUSTA, KENTUCKY, A CORPORATION OF KENTUCKY.

TURNBUTTON FASTENER.

Application filed September 15, 1921. Serial No. 500,931.

To all whom it may concern:

Be it known that I, NATHANIEL YATES, Jr., a citizen of the United States of America, and a resident of Augusta, in the county of Bracken and State of Kentucky, have invented a new and useful Improvement in a Turnbutton Fastener, of which the following is a specification.

My invention relates to a fastener or turn button of the kind commonly used for fastening the curtains of vehicles. The invention consists of various novel features of construction hereinafter described.

An object of my invention is to provide a device of the class described wherein the yielding resistance employed in this sort of a device is more adequately protected than are the similarly functioning elements in devices known to me up to this time.

Another object of my invention is to provide means to be employed with a device of this kind adapted to positively secure the parts thereof in positions for the releasing therefrom or mounting thereon of a curtain.

These and other objects are attained by the means described herein and disclosed in the accompanying drawings, in which

Fig. 1 is a fragmental side elevation of an automobile having mounted upon it certain fasteners embodying my invention.

Fig. 2 is a sectional view through one of the fasteners embodying my invention.

Fig. 3 is a top view of a base forming a detail of my invention.

Fig. 4 is a perspective view of a shell forming a detail of my invention.

Fig. 5 is an enlarged sectional view on line 5—5 of Fig. 2.

The fastener A comprises a base *a* from which extend the slotted flanges *a'* through which screws *a²* extend to mount the fastener on a vehicle body. The body portion or shank *a³* extending from the base is oval in cross section and has a top *a⁴* centrally through which top is formed a bore or perforation *a⁵*. The top of the base has formed in it the radial depressions *a⁶*, *a⁷*, *a⁸* and *a⁹*, of which the depressions *a⁶* and *a⁷* extend in a substantially straight line disposed at substantially right angles to the substantially straight line in which the depressions *a⁸* and *a⁹* extend. A cap *a¹⁰* having a shape substantially oval in cross section has a central bore *a¹¹* in its top *a¹²*, and about the bore is formed a depressed portion *a¹³*

adapted to accommodate a head *a¹⁴* of a pin *a¹⁵*. The bores in the tops of the cap and of the base are in substantial alignment, and the pin *a¹⁵* extends through said perforations. A shell *a¹⁶*, having an oval top *a¹⁷*, has a circumferential flange *a¹⁸* extending from said top *a¹⁷*. The top has formed in it upwardly struck ridges *a¹⁹*, *a²⁰*, *a²¹* and *a²²*, which are adapted to seat in the depressions *a⁶*, *a⁷*, *a⁸* and *a⁹* formed in the top of the base. The shell has a central bore *a²³*, through which the pin *a¹⁵* extends. A spiral spring *a²⁴* is coiled about the pin and abuts the shell and the inner surface of the top of the cap. The pin has an axial bore *a²⁵* in its one end, and the material at this end of the portion of the pin is turned or spread outwardly in any suitable manner, whereby the pin is precluded from separating from the base. The flange *a¹⁸* formed on the shell extends into the cavity in the cap. The sides of the cap are slightly flat and are depressed, as shown at *a²⁶*. The inner walls of the depressed portions of the cap serve to limit the movement of the shell into the cap. Any of the ridges on the shell are adapted to seat in any of the depressions in the top of the base, therefore the cap may be rotated about the pin and may be retained in positions either transversely to or in longitudinal alignment with the base. The spring *a²⁴* yieldingly resists movement of the cap and shell on the base. The depressed portion *a¹³* of the cap and the head of the pin preclude entry of foreign matter into the cap. The shell *a¹⁶* also precludes the entry of foreign matter into the cap.

What I claim is:

1. In a fastener of the class described the combination of a base, a cap and a shell of oval shape having aligned perforations, the base having depressions in its top radiating from the perforation therethrough, ridges formed on the shell radiating from the perforation therethrough, the ridges in the shell being adapted to enter the depressions in the base, a pin extending through the perforations in the cap, the shell and the base adapted to preclude separation of the base, cap and shell, the pin having a head at one end forming a closure for the perforation in the cap and an axial bore in its other end, and having said last mentioned end turned outwardly upon itself to form a bead en-

gaging the base about the perforation therein and a spring mounted on the pin and abutting the cap and the shell.

2. In a fastener of the class described the combination of a base having a slotted top, a cap having a shank and an oval top, the top of the cap having a central slot and a depression formed about said slot, the slot being in alignment with the slot in the base, 5 a pin extending through the slots revolvably mounting the cap on the base and having a head adapted to seat in the depression in the cap, and forming a closure for the perforation in the cap, the pin also having 10 formed in it an axial bore disposed in that portion thereof adjacent the base, said last

mentioned portion of the pin being turned outward upon itself to form a bead engaging the base about the perforation therein, a shell mounted revolvably on the pin 20 engaging the cap and adapted to revolve therewith, a spring contained within the cap abutting the shell and the cap, the shell and base having cooperating ridges and notches adapted, in cooperation with the spring, to 25 yieldingly resist relative movement of the base and plate.

In testimony whereof, I have hereunto subscribed my name this 13th day of September, 1921.

NATHANIEL YATES, JR.
